ABSTRACT

A clear plastic housing contains a plurality of like spherical balls. The housing takes the form of a plurality of concentric spherical shells that are connected together by a plurality of radially extending partitions. The partitions divide the volume between any two neighboring shells into a plurality of arcuate volumes with like radii of curvature and like radial thickness. Each shell that is surrounded by a larger shell bears a plurality of like circular holes in its surface, to connect neighboring volumes in sequence to the spherical volume inside the smallest shell. The diameter of each ball is smaller than the diameter of any holes.

FIG. 1

FIG. 2

PUZZLE TOY

SUMMARY OF THE INVENTION

The object of the invention is to provide an inexpensive puzzle toy for use by people of all ages.

Thus, a spherical housing is divided up into a variety of compartments. Inside the housing is placed a plurality of like spherical balls. The compartments are connected by holes in their walls to form a maze. By manipulating the housing, the balls can be caused to traverse one or more preselected paths, providing an enjoyable toy that requires a satisfying degree of manual dexterity to use.

BRIEF DESCRIPTION OF THE DRAWINGS

FIG. 1 shows the invention in use.

FIG. 2 shows a cross-section of the invention.

DETAILED DESCRIPTION OF PREFERRED EMBODIMENTS

A plurality of hollow spherical shells 10 are concentrically disposed at regular radial intervals between the smallest inner shell 20 and the largest outer shell 30. The shells are held together by radially extending partitions 40 that extend between shells 20 and 30 and divide the volume between any two neighboring shells into a plurality of arcuate volumes 50 that have the same thickness and radius of curvature. Like circular holes 60 in the surfaces of the shells 10 connect neigh-

boring annular volumes together in a sequence that eventually communicates with the central circular volume inside shell 20. The shells and partitions are made of clear plastic and form a housing.

5 Inside the housing is disposed a plurality of like spherical balls 70 that are smaller in diameter than the holes. The various volumes inside the housing thus form a maze through which the balls may be rolled along preselected routes by manipulating the housing.

10 While the invention has been described with detailed reference to the drawings, the protection sought is to be limited only by the terms of the claims which follow.

I claim:

1. A toy, comprising:
a housing taking the form of a plurality of hollow spherical shells concentrically disposed and connected together by a plurality of radially extending partitions that block off the volume between any two neighboring shells into a plurality of arcuate volumes of like radii of curvature and like radial thickness with each shell that is surrounded by a larger shell bearing a plurality of like circular holes in its surface, whereby neighboring arcuate volumes are connected in sequence to the central spherical volumes inside the smallest shell; and
a plurality of like spherical balls disposed in the housing, the diameter of the balls being less than the diameter of the holes.

2. The device of claim 1 wherein the housing is made of clear plastic.
